UNITED STATES PATENT OFFICE.

SOLOMON DAVID GILKERSON, OF MONTREAL, QUEBEC, CANADA.

GARMENT-HOLDING FORM.

1,132,841.

Specification of Letters Patent. Patented Mar. 23, 1915.

Application filed January 28, 1913. Serial No. 744,634.

To all whom it may concern:

Be it known that I, SOLOMON DAVID GILKERSON, a subject of the King of Great Britain, residing at the city of Montreal, in the 5 Province of Quebec and Dominion of Canada, have invented certain new and useful Improvements in Garment-Holding Forms, of which the following is a full, clear, and exact description.

10 This invention relates to improvements in garment holding forms, and the main object is to provide a simple and inexpensive device for holding a garment in its proper shape and proper position in the container 15 during transport.

A further object is to provide a device for holding garments in shape, which may be made so cheaply as to permit of its use with 20 all garments shipped by tailors, valet service concerns, shirtwaist manufacturers and the like.

A still further object is to provide a device which may be used as a form upon which to hang the garment after arrival at 25 its destination.

Another object is to provide a device of this character which when made of the better grades of material may be used as a permanent furnishing for suitcases, trunks, 30 wardrobes and the like.

In its simpler forms, the invention consists of a flat substantially rectangular sheet of suitable material such as cardboard, having two flaps foldable on previously marked lines to form thickened garment shoulder supports. A hanging tab is provided, and may also coöperate with the shipping receptacle to hold the form and garment thereon against movement within the receptacle. 35

40 In the drawings which illustrate the invention:—Figure 1 is a front elevation of the device arranged in operative form, a garment being shown thereon in dotted lines. Fig. 2 is a fragmentary view of the device in the flat form in which it is manufactured. Fig. 3 is a fragmentary perspective view showing the device arranged in and coöoperating with a shipping container.

45 Referring more particularly to the drawings, 5 designates the body of the device which is in the form of a sheet of suitable material irregularly shaped as shown. A pair of large flaps 6 are formed at the upper corners of the body and are separated from 50 one another by a smaller central flap 7. Each flap 6 is connected to the body at a sloping crease or fold 8, which extends from the base of the flap 7 to the side edge of the flap, as clearly seen in Fig. 2. The lower portion of each flap is provided with a 55 crease or fold 9 which commences at the inner end of the crease 8 and extends to the side edge of the flap, said crease diverging slightly from the crease 8 so as to form a narrow triangular portion 10 between the 60 main part of the flap and the body 5. A suitable distance below each fold 8, the body is provided with a substantially semicircular cut 11 forming a tongue 12 under which the upper edge 13 of the flap 6 may be inserted when the flap is folded down over the body, as shown in Figs. 1 and 3. It will be readily understood that when the upper edge of the flap 13 is drawn down, the material will fold at each of the previously 65 marked creases 8 and 9, so that the small triangular portion will assume a position substantially perpendicular to both the body 5 and flap 6, as is clearly shown in Fig. 3. The inner edges of the flap 6 are angularly 70 cut at 14, the angle between the edge portion 14 and the creases 8 and 9 being such that when the flaps are drawn down, the edge portions 14 will abut, as clearly shown in Fig. 1, and hold the flaps against movement 75 toward the vertical center line of the body. In order to hold these flaps against movement away from the vertical center, short angularly disposed cuts 15 are made in the body in such position that the outer corners 80 16 of the flaps may be inserted through these cuts.

The side edges of the body are divided into upper and lower portions 17 and 18 respectively, the upper portions 17 being 85 sloped away from the vertical center while the lower portions 18 curve somewhat sharply toward the center, so that corners 19 are formed at the junction of the edges 17 and 18. A suitable distance below the 90 tongues 12, the body is provided with a large transverse slot 20. The tongue 7 is separated from the body portion by a transverse crease 21 and is divided by a suitably located transverse crease 22. This tongue 7 is 95 further provided with an aperture 23 by means of which the device may be hung up.

This device serves the dual purpose of a hanger upon which to support garments in a wardrobe or store, and a form for holding 100

the garments in shape during transportation. The device also coöperates with the shipping package, so as to be held against movement therein and thus hold the garment comparatively rigid within the container.

It will be clearly understood from the foregoing description that when the flaps 6 are folded down, the triangular portions 10 form thickened garment shoulder supporting portions which prevent the collapse and consequent creasing of the garment shoulders. The tongue 7 projects through the collar of the garment and holds it 15 against lateral movement, while the corners 19 project into the armholes and hold the garment against upward movement. When the holder is designed for use by tailors, valet service concerns or clothing manufacturers, it will be preferably made from a 20 sheet of cardboard or other similar flexible and inexpensive material, so that it may be quickly and easily folded to the form shown in Fig. 1 as required for use. Many garments are shipped in light collapsible cardboard boxes, and when in such a box, a 25 fragment of which is designated in Fig. 3 by the numeral 24, it is desirable to provide one of the edges of the box with a notch or recess 25 in which the tongue 7 may rest, the apertured portion being folded down outside the box at the crease 22. The tongue 30 folds in the opposite direction at the crease 21, so that the holder and garment thereon 35 lie in the bottom of the box. When the cover is placed on the box, it locks the tongue 7 in the notch 25 so that the holder is maintained substantially rigid with respect to the box, and the garment in addition to being held in proper shape is held 40 against sliding around within the box. When used as a garment hanger, the slot 20 permits the insertion of trousers, skirts or other garments on the same holder with the 45 coat or waist. Pads indicated at 26 may be used to prevent collapse of the shoulder supports.

The device has been shown and described as of some material such as cardboard, in 50 order that it may be so inexpensive as to be discarded after being once used. While the use will undoubtedly be greatest in this form, it is obvious that the device may be constructed of more expensive and substantial materials in exactly the same way, for

example of sheet metal. Furthermore, the several parts of the device may be connected by any well known form of hinges in place of merely by folds, without in any way departing from the spirit of the invention, as 60 a fold is merely the most rudimentary form of hinge. When constructed of these more expensive and durable materials, the device could be used as a permanent furnishing of a store display fixture, wardrobe, trunk, 65 suitcase or the like.

Having thus described my invention, what I claim is:—

1. A device of the character described comprising a body portion, flaps foldable 70 thereover to form thickened garment shoulder supports, said flaps having adjacent edges abutting on the center line of the body during folded flap position, tongues formed integral with the body holding said flaps in 75 folded position, and slots formed in the body positioned for the insertion of the remote corners of the flaps and adapted to hold the abutting edges of the flaps against separation. 80

2. A device of the character described comprising a body, a tongue at the center of the upper edge of said body, a pair of flaps extending from the tongue to the side edges of the body and foldable at two creases 85 diverging from the junction of the tongue and body toward the sides of the body, and means for holding said flaps rigidly in folded position.

3. A device of the character described 90 comprising a body portion integral flaps foldable over the body, and extending substantially parallel thereto and having flap parts arranged to form thickened garment shoulder supports, said flap parts extending 95 at substantially right angles to said body and said integral flaps.

4. A device of the character described comprising a body portion, flaps foldable over said body portion a triangular flap 100 part connecting said flap and body adapted to form thickened garment shoulder supports, said flaps having adjacent edges abutting during folded flap position.

In witness whereof I have hereunto set 105 my hand in the presence of two witnesses.

SOLOMON DAVID GILKERSON.
